COMBINATION BATHTUB AND SHOWER STALL

James A. Osika, Urbana, Ill., assignor to Whirlpool
Corporation, a corporation of Delaware

Filed Apr. 11, 1966, Ser. No. 1,829

Term of patent 14 years

(Cl. D4—4)

I claim:

The ornamental design for a combination bathtub and shower stall, as shown.
